assignor to
Delorah Powers, Albert E. Powers, and Nath'l B. Powers
Letters Patent No 13411. Dated, Sept. 2, 1857.

The schedule referred to in these letters patent
and marking part of the same.

To all whom it may concern:

Be it known that I,
James Hutchinson of Troy, in the county of Rensselaer and state
of New York, have invented or produced a new design
or figure to be printed upon floor oil cloths, and I do
hereby declare that the following is a full & exact des-
cription of the same, viz:

The pattern consists of a se-
ries of rosettes placed upon circular grounds at some distance
from each other, which grounds are enclosed in a border
of similar colors to the rosettes.

These borders are connected
with each other by ornamental bars or stiles of similar shades
of color and with the circles separate the remaining portion
of the pattern into two somewhat irregular shaped grounds
one of which is so colored as to represent a panel of wood,
having its centre raised, and the other has a group of
leaves represented upon a plain ground of different color
from the circular grounds, the general arrangement and
details of the pattern being shown upon the annexed copy or
drawing, which forms part of this specification.

And what is claimed
as my invention, and desired to be secured by Letters
Patent of the United States, is the arrangement of fi-
